UNITED STATES PATENT OFFICE.

HERBERT DUDLEY BARLOW, OF LONDON, ENGLAND.

LIFT OR THE LIKE.

SPECIFICATION forming part of Letters Patent No. 767,541, dated August 16, 1904.

Application filed December 11, 1903. Serial No. 184,831. (No model.)

To all whom it may concern:

Be it known that I, HERBERT DUDLEY BARLOW, a subject of the King of Great Britain and Ireland, residing at 237 Shaftesbury avenue, London, W. C., England, have invented certain new and useful Improvements in and Relating to Lifts or the Like, of which the following is a specification.

The invention relates to two-point lifts and the like of the type described in Patent No. 737,313, dated August 25, 1903, and has for its object to improve the mechanism of such lifts structurally, so that the different parts may be better adapted to withstand the forces acting upon them.

A further object of the invention is to increase the travel of the lift-cage with the same diameter of crank-circle and the same multiplying-gear.

The invention consists in a mechanism comprising crank elements or the like geared together and carrying pins on which the sheaves of a multiplying-tackle are journaled, the pins being so disposed that they approach and recede from each other with an approximately simple harmonic motion as the wheels carrying them rotate.

Referring to the accompanying drawings, Figure 1 is a plan of one form of the invention, Fig. 2 being as to its left-hand half an outside elevation and as to its right-hand half a sectional elevation on the line X-X of Fig. 1. Figs. 2^a and 2^b show other methods of anchoring and leading off the tackle-rope. Fig. 3 shows diagrammatically a plan of a modified form of mechanism. Fig. 4 shows a corresponding sectional elevation, while Fig. 5 is a view of another modification adapted to give a dwell at the ends of the travel of the lift-cage.

In carrying the invention into effect according to one form, as shown in Figs. 1 and 2, a worm *a*, mounted on the motor-shaft *b*, drives a second shaft *c* by means of the worm-wheel *d*. The shaft *c* has two pinion-wheels *d* rigidly secured to it, and these each gear with spur-wheels *e* *f* of equal diameter, arranged in pairs, as shown, at diametrically opposite points with regard to the axis of the shaft *c*. The shafts on which the spur-wheels *e* *f* and

the pinion-wheels *d* are mounted are journaled in suitable bearings carried by the standards *h*. The worm-wheel *d* may also be conveniently journaled in bearings supported by one of these standards. The wheels *e*, forming the one pair, carry a crank-pin *i* between them at the required radius, the wheels acting as ordinary disk cranks. A second crank-pin *k* is similarly carried at the same radius by the other pair of wheels *f*. The crank-pins *i* and *k* are so disposed with relation to each other that they are equidistant from the axis of the pinion-shaft *c*, while a line joining their centers passes through the axis. It will be obvious from considerations of symmetry that if this is true in any one position of the gear it will be true in all positions. Hence if the sheaves *m*, carried by the crank-pins *i* and *k* and round which the rope *n* is wound to form a multiplying-tackle, are of a diameter sufficiently greater than that of the pinion-shaft *c* the falls of the tackle will in all positions of the mechanism pass clear of the pinion-shaft *c*.

One end of the rope is anchored to a shackle or the like, *o*, the other end being taken to the lift-cage either directly or by way, for example, of a pulley *p*, sleeved on the shaft *c*. (See Figs. 2^a and 2^b.) The shackle, if desired, may also be sleeved on the shaft *c*.

It will be seen that as the spur-wheels *e* and *f* revolve the crank-pins *i* and *k* approach and recede from each other with an approximately simple harmonic motion which is copied by the lift-cage on an enlarged scale.

The form of the invention just described is suitable for lifts of a heavy nature, as overhung parts can be avoided and double bearings provided in all cases. It will be seen, however, that if overhung parts are not considered undesirable the wheels *e* *f* and other parts do not need to be in duplicate. For equal diameters of the crank-pin circles it will be seen that compared to the form of mechanism described in the former patent referred to above the travel of the lift-cage is doubled.

Referring to Figs. 3 and 4, a modified form is shown, the reference-letters being the same as before. The wheels *e* and *f* in this case

are geared directly together, and thus revolve in opposite directions. The crank-pins *i* and *k* are so set that the line joining them is parallel to the line through the centers of the wheels *e* and *f*, while at the same time the crank-pins are at equal distances from the point of contact of the pitch-circles of these wheels. This modification also leads to an efficient structural disposition of parts.

- 10 Referring to Fig. 5, another modification is shown diagrammatically in which two independent ropes *n* *n'* are adopted, each operated from its own crank-pins *i* *k* and *i'* *k'*, respectively, the two pairs of crank-pins being slightly out of phase, as shown. The pairs of crank-pins shown in full and dotted lines in the figure are each mounted on their own separate wheel-cranks, all four of which are driven from the one pinion-shaft indicated if 15
- 20 the gearing of Figs. 1 and 2 be adopted. The ropes are attached not directly to the cage *s*, but to each end, respectively, of a rocker or the like, *t*, pivoted to the cage at its center point. The effect of this arrangement is 25 that a "dwell" is secured at each end of the travel of the cage, a point which is of considerable importance in the case of continuously-running lifts.

It will be evident without further description that the modification of Figs. 3 and 4 may equally well be arranged with duplicate tackle and rocker. Any of the described methods of anchoring and leading off the cage-ropes may also be adopted.

35 An electric motor *r* is shown for driving the mechanism described; but power may be supplied in any other convenient manner.

It will be seen that overrunning in a lift of this description is impossible. Starting and 40 stopping take place gradually, while the direction of the motor does not need to be reversed.

Having now described my invention, what I claim as new, and desire to secure by Letters 45 Patent, is—

1. A lift mechanism comprising, in combination, crank elements geared together; means for rotating said crank elements; crank-pins mounted on parts of said crank elements 50 which alternately recede from and approach one another, together with tackle connecting said crank-pins to the cage to be operated.

2. A lift mechanism comprising, in combination, crank elements geared together, means for rotating said crank elements, crank-pins mounted on parts of said crank elements which alternately recede from and approach one another, sheaves journaled on said crank-pins together with a multiplying - tackle wound 6c round said sheaves and connected to the cage to be operated.

3. A two-point lift mechanism comprising, in combination, crank elements geared together, so as to rotate in the same direction; 65 means for rotating said crank elements;

crank-pins mounted on oppositely-movable parts of said crank elements; sheaves journaled on said crank-pins together with a multiplying-tackle wound round said sheaves and connected to the cage to be operated.

70

4. A two-point lift mechanism comprising, in combination, spur-wheel cranks; a shaft disposed directly between said wheel-cranks, pinion-wheels mounted on said shaft, and gearing with said wheel-cranks, means for rotating said pinion-shaft; crank-pins mounted on said cranks, said crank-pins being disposed in side elevation, on a straight line through the center of said pinion-shaft and at equal distances from said center; sheaves journaled on said crank-pins together with multiplying-tackle wound round said sheaves and connected to the cage to be operated, substantially as set forth.

75

5. A two-point lift mechanism comprising, in combination, two pairs of spur-wheel cranks, bearings on the outer sides of each coaxial pair; a shaft disposed directly between said wheel-cranks; pinion-wheels mounted on said shaft and gearing with said wheel-cranks; 80 bearings for said shaft on the outer sides of said pinions; means for rotating said shaft; crank-pins mounted on and between said coaxial pairs of wheel-cranks, one to each pair, said crank-pins being disposed in side elevation on a straight line through the center of said pinion-shaft and at equal distances from said center; sheaves journaled on said crank-pins together with multiplying-tackle wound round said sheaves and connected to the cage 85 to be operated, substantially as set forth.

90

6. A two-point lift mechanism comprising, in combination, two pairs of spur-wheel cranks, bearings on the outer sides of each coaxial pair; a shaft disposed directly between 95 said wheel-cranks; pinion-wheels mounted on said shaft and gearing with said wheel-cranks; bearings for said shaft on the outer sides of said pinions; means for rotating said shaft; crank-pins mounted on and between said coaxial pairs of wheel-cranks, one to each pair, 100 said crank-pins being disposed in side elevation on a straight line through the center of said pinion-shaft and at equal distances from said center; sheaves journaled on said crank-pins together with multiplying-tackle wound round said sheaves and connected to the cage to be operated, substantially as set forth.

105

6. A two-point lift mechanism comprising, in combination, two pairs of spur-wheel cranks, bearings on the outer sides of each coaxial pair; a shaft disposed directly between said wheel-cranks; pinion-wheels mounted on said shaft and gearing with said wheel-cranks; bearings for said shaft on the outer sides of said pinions; means for rotating said shaft; crank-pins mounted on and between said coaxial pairs of wheel-cranks, one to each pair, 110 said crank-pins being disposed in side elevation on a straight line through the center of said pinion-shaft and at equal distances from said center; sheaves journaled on said crank-pins; a sleeve element rotatably mounted on said pinion-shaft together with multiplying-tackle wound round said sheaves and connected to the cage to be operated, one end of 115 said tackle being anchored to said sleeve element, substantially as set forth.

120

7. A two-point lift mechanism comprising, in combination, two pairs of spur-wheel cranks, bearings on the outer sides of each coaxial pair; a shaft disposed directly between 125 said wheel-cranks; pinion-wheels mounted on said shaft and gearing with said wheel-cranks; bearings for said shaft on the outer sides of said pinions; means for rotating said shaft; crank-pins mounted on and between said coaxial pairs of wheel-cranks, one to each pair, 130 said crank-pins being disposed in side elevation on a straight line through the center of said pinion-shaft and at equal distances from said center; sheaves journaled on said crank-pins together with multiplying-tackle wound round said sheaves and connected to the cage to be operated, substantially as set forth.

axial pairs of wheel-crank, one to each pair, said crank-pins being disposed in side elevation on a straight line through the center of said pinion-shaft and at equal distances from said center; sheaves journaled on said crank-pins; a sleeve element and a pulley rotatably mounted on said pinion-shaft together with multiplying-tackle wound round said sheaves and connected by way of said pulley to the car to be operated, one end of said tackle being secured to said sleeve element, substantially as set forth.

8. In lift mechanism in which the cage receives a harmonic motion from one or more cranks, means for giving the cage a "dwell" at the ends of its travel, consisting in combination of crank-pins revolving out of phase together with sets of tackle connected between

said out-of-phase crank-pins and the cage, substantially as set forth.

9. A lift mechanism comprising, in combination, crank elements geared together; means for rotating said crank elements; pairs of crank-pins mounted on parts of said crank elements which alternately recede from and approach one another, one of said pairs having a lead with regard to the other; a lift-cage; a rocker mounted on said cage together with duplicate tackle connected respectively to the ends of said rocker, substantially as set forth.

In witness whereof I have hereunto set my hand in presence of two witnesses.

HERBERT DUDLEY BARLOW.
